UNITED STATES PATENT OFFICE.

FREDERICK RUDOLPH CHRISTIAN STRÜVER, OF PINE CREEK, DARLING DOWNS, QUEENSLAND.

DESIGN FOR A BUTTER-FORK.

SPECIFICATION forming part of Design No. 20,400, dated December 9, 1890.

Application filed November 5, 1890. Serial No. 370,427. Term of patent 14 years.

To all whom it may concern:

Be it known that I, FREDERICK RUDOLPH CHRISTIAN STRÜVER, grazier, a subject of the Queen of Great Britain, residing at Pine Creek, Darling Downs, in the British Colony of Queensland, have invented and produced a new and original Design for a Fork for Working up Butter, of which the following is a specification.

10 In the drawings I have shown my design, in Figure 1, by a side elevation, and in Fig. 2 by a plan view.

15 The leading features of my design consist in a number of prongs which are parallel and slightly curved and having upwardly bent or curved rear ends, an upwardly and rearwardly curved butt portion, and a handle which curves upwardly and rearwardly from said butt portion and is made tapering from its 20 upper to its lower end.

A indicates the prongs, which are parallel and slightly curved, as shown. The rear ends of the prongs are bent or curved upwardly more decidedly, as seen at C. The butt portion D of the fork curves upwardly from the 25 rear ends of the prongs and then rearwardly. B is the handle, which curves upwardly and rearwardly from the butt and gradually tapers from its upper to its lower end, where it joins said butt.

30 What I claim is—

The design for a butter-fork, as herein described and shown.

FREDERICK RUDOLPH CHRISTIAN STRÜVER.
